UNITED STATES PATENT OFFICE.

CHRISTOPHER C. SHELBY, OF PATERSON, NEW JERSEY.

BUSTLE.

SPECIFICATION forming part of Letters Patent No. 395,183, dated December 25, 1888.

Application filed April 23, 1888. Serial No. 271,599. (No model.)

To all whom it may concern:

Be it known that I, CHRISTOPHER C. SHELBY, of Paterson, in the county of Passaic and State of New Jersey, have invented certain new and useful Improvements in Bustles; and I do hereby declare the following to be a full, clear, and exact description of the same, reference being had to the accompanying drawings, forming a part of this specification, and to the figures and letters of reference marked thereon.

My invention relates particularly to a novel construction of the bustle-frame, and, secondly, to an improved construction and arrangement of springs for keeping the bustle normally expanded.

In the accompanying drawings, Figure 1 represents a perspective view of a bustle embodying my improvements; Fig. 2, a side elevation of the same closed up, its appearance when expanded being also shown in this figure in dotted lines; Fig. 3, a similar view of still another modification. Fig. 4 is a view of the modified form of spring.

Similar letters of reference in the several figures indicate the same parts.

The letter A indicates the main frame of the bustle, consisting, preferably, of a metal cloth-covered reed bent and secured in elliptical form, as shown. To this frame are pivoted by spring-arms B a series of reeds, C, that are connected together by a tape, D. Each of the spring-wires B has one end, b, secured by a clamp, a, or otherwise to the outside of the main-frame reed A, thence passing down and through said main reed at a', and through the ends of the securing-reeds C to the other side of the bustle, where it passes through the main reed again at a'', and thence proceeds at right angles in the form of an arm, b', as shown in Fig. 1. This arm is adapted to be swung upward, so as to engage with a hook or other fastening device, F, on the bottom reed, C, such swinging up putting the body of the spring-wire under torsional strain and causing the arm to exert sufficient pressure on the said bottom reed, C, to keep the whole bustle expanded, as shown in Fig. 1.

By the employment of the open hooks F for retaining the ends of the spring-wires the con-

nexion between the spring-wires and the bottom reed is enabled to be easily and quickly made, while the requisite amount of play which said wires require when the reeds are folded up is afforded. In order that the ends of the wires may not injure the clothing of the wearer, I preferably form them into loops, as shown.

Instead of securing one end of each of the spring-wires to one side of the frame and extending said wire across to the other side and forming it into a spring arm or lever, as shown in Fig. 1, I may cause each of said spring-wires to extend part way across the frame, and then bend it so as to return it to the same side from whence it started and form its end into an arm or lever for engaging a hook on the bottom reed, as shown in Fig. 4.

The elliptical form of the main reed or frame is well calculated to maintain the bustle in shape and prevent any disarrangement of its parts.

Having thus described my invention, what I claim as new is—

1. In a bustle, the combination, with the main reed, the waistband, and collapsible hoop-reeds pivoted to the main reed, of the spring for distending the hoop-reeds, passing through a hoop-reed and connected to the main reed at one end to form the pivot for said hoop-reed, its opposite end passing through the main reed at a point removed from the pivotal point of the hoop-reed, and a connection between the spring and hoop-reeds, substantially as described. 85

2. The combination, with the main reed, the waistband, and collapsible hoop-reeds pivoted to the main reed, of the spring-wires for distending the hoop-reeds, connected to the main reed at one end and forming the pivots for said hoop-reeds, the other end of said spring-wires passing through the main reed at points slightly removed from the pivotal points of the hoop-reeds, and loose connections between the hoop-reeds and springs, substantially as described. 95

CHRISTOPHER C. SHELBY.
